[57] CLAIM

The ornamental design for a toy tote, as shown and described.

DESCRIPTION

FIG. 1 is a perspective view of the toy tote;

FIG. 2 is a front view of the toy tote;

FIG. 3 is a side view of the toy tote;

FIG. 4 is a rear view of the toy tote;

FIG. 5 is a top plan view of the toy tote; and,

FIG. 6 is bottom plan view of the toy tote.

The strap in FIGS. 2-6 has been shown broken away for ease of illustration.

The broken line showing of a toy in FIG. 1 is for illustrative purposes only and forms no part of the claimed design.
